(57) **CLAIM**

The ornamental design for a container for drinks, as shown and described.

DESCRIPTION

The article is a plastic container, possibly for drinking water, which has a curved shoulder and a bellows barrel.

FIG. 1 is a front view of a container showing my design, with all other sides being identical;

FIG. 2 is a top plan view thereof;

FIG. 3 is a bottom plan view thereof;

FIG. 4 is a front view thereof in collapsed condition;

FIG. 5 is a cross-sectional view thereof, in a collapsed condition taken at line 5—5 of FIG. 2; and,

FIG. 6 is a cross sectional view thereof taken of area 6 of FIG. 1.

1 Claim, 4 Drawing Sheets

FIG. 1**FIG. 6**

FIG. 2**FIG. 3**

FIG. 4

FIG. 5

FIG. 6
